[57] ABSTRACT

Apparatus for generating light utilizing the principle of electrostatic induction between two relatively moving dielectric materials of opposite polarity. A first hollow member is filled with an ionizable gas and includes at least one electrode supported in close proximity to the inner surface of the member. A second member formed of a dielectric material of opposite polarity partially surrounds the first member in close proximity thereto. The two members are moved relative to one another and the consequent electrostatic induction ionizes the gas within the first member.

LIGHT GENERATING APPARATUS

BACKGROUND OF INVENTION

The present invention is concerned with light generating machines and, more specifically, with apparatus utilizing the principle of electrostatic induction and ionization of gases.

The principle of static electricity or electrostatic induction has been known for some time. Particularly, it is known that two dielectric materials of opposite polarity, when rubbed together or brought into close proximity with one another, will result in polarization of the materials with consequent change in the potential of the respective members. This is the principle which is employed in the well known Van de Graaff generator within which static charges of many thousands of volts are generated.

Very little practical use of the principle of electrostatic induction has been made. The Van de Graaff generator and similar types of machines represent one of the few practical applications of the principle. Except for those few limited applications, the principle still remains today more of a novelty or curiosity than of practical value.

OBJECT AND SUMMARY OF THE INVENTION

It is the object of the present invention to provide a light generating machine utilizing the principle of electrostatic induction.

The foregoing object is carried out in the present invention by providing a first hollow enclosed member which is formed of dielectric material and which is filled with an ionizable gas. In a preferred embodiment, the first hollow member is preferably formed of a transparent or translucent glass and includes at least one electrode supported within the hollow member in close proximity to the inner surface of the member.

A second member is formed of a dielectric material of opposite polarity to that of the first member. In the preferred embodiment, the second member is formed of plastic. The first and second members include a portion of their surfaces which are of complementary configuration such that one member may be rotated relative to the other. The consequent relative motion between the first and second members results in electrostatic induction between the dielectrics of opposite polarity. The polarization which results from the electrostatic induction is impressed across the electrodes within the first hollow member. The polarization of the gases and the heavy sparking across the electrodes causes ionization of the gas within the member with consequent generation of light by reason of the ionization.

In one species of the invention, the hollow gas filled member is held stationary while in another species thereof, the hollow enclosed member is rotated. Additionally, in a further species of the invention, the first and second members are of a complementary cylindrical configuration whereas in yet another species thereof, they are formed of a complementary conical configuration.

Other objects and advantages of the present invention will become apparent to those skilled in the art from the detailed description thereof made in conjunction with the drawings which follows:

DETAILED DESCRIPTION OF DRAWINGS

FIG. 1 is an assembled perspective view of one species of the light generating apparatus of the present invention;

FIG. 2 is an exploded perspective view of the apparatus of FIG. 1;

FIG. 3 is an assembled perspective view of a second species of light generating apparatus of the present invention; and

FIG. 4 is an exploded perspective view of the apparatus of FIG. 3.

DETAILED DESCRIPTION OF INVENTION

One species of the light generating apparatus of the present invention is shown in FIGS. 1 and 2 of the drawings. A main supporting frame 10 is provided. At one end of the supporting frame 10 there is positioned a clamping ring 12. The clamping ring includes a relief slot 13 cut through the base of the ring. A nut and bolt 15 and 14 respectively are provided and are utilized through an aperture 16 to contract the ring for the purpose hereinafter described.

The opposite end of the main supporting frame 10 includes a vertical support 17. The vertical support includes a notch 18 in the lower portion thereof which is adapted to fit over complementary notches 19 formed into the end of the main supporting frame 10. A nut and bolt combination 20 and 21 respectively are utilized through bolt holes 22 and 23 in the vertical and main supporting members respectively to hold the vertical member rigidly in place.

The apparatus includes a bulb 24 within which the light is generated. The bulb 24, in the species of FIGS. 1-2, is of a generally elongate cylindrical configuration. The bulb is hollow and enclosed on both ends. The bulb is of a first diameter through approximately 180° of the circumference of the bulb and of a smaller diameter through the remaining 180° of circumference to form a recess 28 which extends throughout substantially the entire length of the bulb.

A flange 25 at one end of the bulb is provided in order that that end of the bulb will be a true circle equal to the larger diameter of the bulb. A locating projection 26 is provided upon the upper circumference of the bulb and is of a width corresponding to the width of a slot 27 in the upper end of the clamping ring 12.

The bulb 24 is hollow. At the time of manufacture, the bulb is evacuated and filled with an ionizable gas such as neon or argon. A pair of electrodes 29 and 30 are supported within the bulb upon supports 31 and 32 secured into the end wall 33 of the bulb. The electrodes terminate in a spherical configuration at their extreme ends. The spheres on the electrodes are positioned in close proximity to the inner circumference of the recessed portion 28 of the bulb. In a preferred arrangement, the electrodes 29 and 30 are spaced axially within the bulb one-third of the axial distance from each end. Additionally, the electrodes are spaced angularly one from another approximately 45° in opposite directions from a vertical line through the bulb.

The light of the present invention further includes a lens 34. The lens is preferably of a conical configuration on one end 35. The opposite end includes a circular projection or flange 36 of a diameter corresponding to the inside diameter of the clamping ring 12. In a pre-

ferred arrangement, the lens 34 is formed of a transparent plastic material preferably of red color.

In assembled position, the flange 25 of the bulb 24 is designed to fit within the clamping ring 12. The projection 26 of the bulb is located within the ring in the slot 27. In a like manner, the flange 36 of the lens 34 is positioned into the clamping ring 12 from the opposite end. When the bulb and lens are in place, the bolt and nut arrangement 14 and 15 respectively is tightened to secure the lens and bulb within the clamping ring.

The light of the present invention further includes a collector 37. The collector is preferably formed of a plastic material. The collector is of a hollow elongate cylindrical configuration which is open at one end and closed at the opposite end in a cup shaped supporting member 38.

The cylindrical portion of the collector 37 is of length equal to the bulb 24 excluding the flange 25 of the bulb. The inside diameter of the cylindrical portion of the collector 37 is equal to the larger diameter of the bulb 24. The collector includes three elongate slots 39 which run for the length of the cylindrical portion of the collector. The slots 39 divide the collector into three equal arcuate portions.

In assembled position, the collector 37 is positioned over the outer circumference of the bulb 24 and is supported for rotation upon the vertical support 17. Specifically, a bearing 79 is press fitted into a bore 40 in the rear of the supporting member 38 of the collector. A hollow elongate shaft 41 is pressed into a bore 42 in the upper end of the vertical support 17. The shaft 41 is pressed through the bore 42 so as to extend beyond the other side of the support 17. Thereafter, the inner race of the bearing 79 is forced upon the shaft 41.

A flexible drive cable 43 is employed to rotate the collector 37. The flexible cable 43 and its inner drive cable 44 pass through a drilling 45 in the shaft 41. A drive tang 46 is secured to the inner drive cable 44 at its end. The drive cable is held in place by means of a lock nut 47 which pulls a shoulder 48 secured to the cable against a nut 49 which is pressed onto the shaft 41.

The supporting member 38 includes a rectangular aperture recessed in the bore 40 of configuration complementary to the tang 46. When in assembled position, the tang 46 rests within the aperture to impart the driving force to the collector 37. Any suitable means may be employed to drive the inner cable 44 to rotate the collector 37.

In operation, rotation of the plastic collector 37 around the glass bulb 24 will result in electrostatic induction between the two dielectric materials of opposite polarity. Passage of the arcuate cylindrical portions of the collector from the portion of the bulb of the largest diameter to the portion thereof of smaller diameter provides an alternating separation of the two dielectric materials resulting in alternating polarization of the glass bulb. The resultant potential created by this alternating polarization results in alternating potentials across the electrodes 29 and 30 within the bulb. The sparking resulting from the alternating potential will ionize the gas within the bulb and consequently light the bulb. The light within the bulb will be focused through the lens 35.

A second species of the light generating apparatus of the present invention is shown in FIGS. 3 and 4. In this species, the bulb 50 is likewise a hollow enclosed mem-

ber but of conical configuration. The bulb includes two electrodes 51 and 52 which are supported on a common support member 53 which is secured in place at one end of the apex of the conical bulb.

The electrodes 51 and 52 are positioned on the support member 53, 180 degrees apart and are spaced from one another axially along the support member 53 but generally toward the larger end of the bulb. The electrodes extend to approximately one-eighth of an inch from the inner surface of the bulb. The bulb 50 is preferably formed of glass material. During manufacturing, the bulb is evacuated and filled with an ionizable gas such as neon or argon.

The bulb 50 has included therein a threaded metallic shaft 54. This shaft is used to support the bulb and for rotating of the bulb in a bearing member which will be described hereinafter.

The light also includes a plastic collector 55. The collector is of a conical configuration which includes an inside configuration equaling the outside configuration of the bulb 50 in order that the bulb may nest within the plastic collector. The collector includes three elongated slots 56 which divide the collector into three equal arcuate segments. The collector terminates at its apex in a threaded ring 57 which is utilized to support the collector as hereinafter described.

The bulb 50 and collector 55 are supported within a circular support housing 58. The support housing 58 includes an annular internally threaded recess 59. The inside diameter of the recess 59 corresponds to the outside diameter of the supporting ring 57 of the collector. During assembly, the collector 55 is threaded into the recess 59 and remains stationary. A downwardly extending support 60 extends from the support housing 58 and is utilized to secure the entire light to a supporting structure.

The support housing 58 further includes a recessed boss 61. The boss includes a bore in the back side thereof which is adapted to receive a bearing 62 in a press fit. Once the bearing 62 is in place, the shaft 54 of the bulb 50 is positioned through the bore 63 in the boss 61 and extends through the inner race of the bearing 62. A lock nut 64 is threaded onto the shaft 54 and holds the shaft and bulb in place for rotation.

The light generating apparatus further includes a reflector cover 65. The reflector is of a conical configuration like the bulb 50 but is large enough to permit the collector to be positioned within the reflector 65. The reflector, at its smaller end, includes an inwardly turned flange 66. The reflector is formed of a resilient plastic. During assembly, the flange 66 of the reflector is forced over the housing 58 and passes into an annular groove 67 which secures the reflector to the housing 58.

The opposite end of the reflector 65 includes an opening 68 which is defined by a second inwardly turned flange 69. The diameter of the opening 68 is large enough to permit the larger end of the collector to be forced past the resilient flange 69 of the reflector.

The reflector is formed of a transparent plastic material. The outside surface of the reflector is coated with a mirror material. During operation of the light, the light generated within the bulb 50 will be reflected from the inner surface of the reflector and ultimately be shined through the opening 68.

The rear of the light is enclosed by a cover cap 78. The cap includes a bore 80 in the central portion

thereof which permits clearance for the lock nut 64 when the cap is in place. Two drillings 70 and 71 are provided in the cap. Cap screws 72 pass through the drilling and are threaded into corresponding threaded holes (not shown) in the housing 58 to secure the cap 5 in place. The bore 80 in the cap 78 includes a further drilling (not shown) through the back of the cap 78.

Rotary motion is imparted to the bulb 50 by means of a flexible drive cable 73. The outside housing 76 of the cable is positioned in the drilling in the rear of the cap 78. A threaded tang 74 is provided on the end of the inside cable 75. The threaded tang threads into a threaded hole 77 in the end of the shaft 54 of the bulb. Rotation of the inside cable 75 is in a direction to maintain the tang threaded within the hole 77 and thus hold 15 the entire cable in position.

In operation, the inside cable 75 of the flexible cable is driven by any suitable means. The inside cable causes the glass bulb 50 to rotate within the plastic collector 55. The relative motion of the two dielectrics of opposite polarity results in electrostatic induction which polarizes the bulb 50. The slots 56 in the collector 55 result in alternating polarization within the bulb 50 as the electrodes 51 and 52 pass by the slots. The resultant polarization of the bulb 50, by reason of the potential 20 within the bulb 50, results in sparks which ionize the gas and cause light emission from the bulb.

The light generating apparatus of the present invention has many uses, one contemplated use is as the headlight and/or taillight of a bicycle. In that use, a 30 drive mechanism driven by the wheel of the bicycle would be utilized to impart the motion to the inner cable of the flexible cable.

The light generating apparatus of the present invention has been described in respect to a particular embodiment thereof. Other variations and modifications of the present invention will now become apparent to those skilled in the art in view of the foregoing disclosure. No limitation as to the scope of the invention was intended by reason of the particular disclosure thereof 35 but the scope of the invention is to be interpreted in

view of the appended claims.

I claim:

1. Light generating apparatus comprising:
a first elongate hollow enclosed member formed of a dielectric material and filled with an ionizable gas;
at least one pointed electrode supported within the enclosed member and spaced in close proximity to the inner surface of the hollow member;

a second member formed of a dielectric material of polarity opposite to the first member substantially surrounding the first member and of complementary configuration thereto along the longitudinal axis thereof;
a plurality of elongate slots within the second member parallel to the longitudinal axis thereof; and
means for moving the first and second members relative one to another whereby electrostatic induction generated between the members will ionize the gas within the first member with consequent light emission.

2. The apparatus of claim 1 wherein the first member is formed of a transparent glass and the second member is formed of a plastic material.

3. The apparatus of claim 1 wherein the first member is stationary.

4. The apparatus of claim 1 wherein the second member is stationary.

5. The apparatus of claim 1 wherein the first and second members are of complementary cylindrical configuration.

6. The apparatus of claim 5 further including a transparent lens secured to the first member at one end thereof.

7. The apparatus of claim 1 wherein the first and second members are of complementary conical configuration.

8. The apparatus of claim 7 further including a third member surrounding the second member and including a reflective material on the outer surface thereof.
